UNITED STATES PATENT OFFICE.

ISIDOR KITSEE, OF PHILADELPHIA, PENNSYLVANIA.

PRINTING APPARATUS.

1,092,490.

Specification of Letters Patent.

Patented Apr. 7, 1914.

Application filed October 31, 1912. Serial No. 728,773.

To all whom it may concern:

Be it known that I, ISIDOR KITSEE, a citizen of the United States, residing in the city of Philadelphia, county of Philadelphia, 5 and State of Pennsylvania, have invented Improvements in Printing Apparatus, of which the following is a specification.

My invention relates to apparatus for facilitating the printing of positive or negative moving picture films, these continuous films having thereon picture units of a cinematographic series, from negative or positive films. To this end I provide a cylinder or the like of transparent or translucent 10 material, such as glass, and wind helically thereon the film from which prints are made, and superimpose upon such film the sensitized film disposed in like helical path, means being provided for producing light 15 within the cylinder to affect the superimposed or sensitized film through the film directly upon the cylinder.

My invention resides in apparatus of the character described and in the features hereinafter described and claimed.

For an illustration of one of the forms my invention may take reference is to be had to the accompanying drawing, in which:

Figure 1 is a longitudinal sectional view, 30 some parts in elevation, of a form my invention may take. Fig. 2 is a cross sectional view taken on the line A—A of Fig. 1, showing parts in elevation. Fig. 3 is a side elevational view of the printing cylinder removed to separate supports where the films may be wound upon it. Fig. 4 is a sectional view, parts in elevation, taken on the line B—B of Fig. 3. Fig. 5 is a fragmentary cross sectional view through a part of the 35 cylinder and the films thereon.

Referring to Fig. 1, 1 is any suitable base upon which are secured the supports 2 and 3 having at their upper ends bearings 4 and 5 respectively, these bearings being open 40 at the top so that the cylinder C may be lifted out of these bearings. The cylinder C, of glass or other suitable transparent or translucent material, is supported on the end spiders 6 and 7, the spider 6 having the hollow shaft extension 8 resting in the bearing 5, and the spider 7 having the shaft extension 9 resting in the bearing 4. Upon the hollow shaft 8 is secured a pulley 10 for rotating the cylinder, as hereinafter described.

Upon the base 1 may be provided supports 11 carrying rods 12 upon which may be slid

the arms 13 supporting the base 14 of an electric lamp L which extends freely through the hollow shaft 8 and substantially the entire length of the cylinder C, preferably in the axis thereof. The base 14 carries binding posts 15, 15 to which are connected the electric service wires 16 for delivering current to the electric lamp L. By moving the arms 13 toward the right, the lamp L may be entirely withdrawn from the cylinder C and from the hollow shaft 8 so that the cylinder C may be lifted from its bearings 4 and 5.

Wrapped helically around the outer surface of the cylinder C is the picture film 17 from which prints are to be made. The film 17, either a positive or negative, may be called the master film. Such a moving picture film has perforations in its margins, 70 and at suitable intervals in the helical path of the film 17 are pins 18 carried by the cylinder C, certain perforations in the film passing over these pins, whereby the film is securely held in place upon the cylinder. 75 Then a similar perforated sensitized film 19 is wound upon the cylinder C directly on top of the master film 17, certain perforations in the film 19 embracing the same pins 18, whereby both films are kept in proper relation with respect to each other and securely upon the cylinder C. Of course the sensitized film 19 is wound on top of the film 17 in a dark room or in such light as will not affect the film 19. Then the current is 80 turned on through lamp L for a suitable time and the exposure of the sensitized film 19 through the master film 17 is made. Then the exposed film 19 may be unwound from the cylinder C and developed in the usual 85 way, and a new sensitized film 19 placed upon the cylinder C in register with the film 17 for another exposure.

For the purpose of winding the films upon the cylinder C a pulley 10 may be provided 100 driven by belt from any suitable means to rotate the cylinder for the winding or unwinding operation. Or the lamp L may be withdrawn to the right and the cylinder removed from the apparatus shown in Fig. 1 105 and placed in separate supports 2' and 3' for the winding operation, the exposures only being made in such case in the apparatus shown in Fig. 1.

What I claim is:

1. In film printing apparatus, the combination with a light transmitting cylinder, of

a plurality of members disposed in a helical path on said cylinder and adapted to enter into marginal perforations in master and sensitized films, whereby said films are held 5 in superposed position on said cylinder and in helical relation with respect thereto, and means for producing light within said cylinder.

2. The combination with a hollow light 10 transmitting cylinder, of a hollow bearing therefor, a spider supporting said cylinder on said bearing light producing means, and a guide upon which said light producing means may be moved longitudinally of said 15 cylinder through said spider and hollow bearing.

3. The combination with a hollow light transmitting cylinder, of a hollow bearing therefor, a spider supporting said cylinder 20 on said bearing, an incandescent electric

lamp, and a guide upon which said lamp is movable longitudinally of said cylinder through said spider and hollow bearing.

4. In film printing apparatus, the combination with a film supporting member, of 25 a master film wrapped upon said supporting member in a helical path, means adapted to hold a sensitized film in a helical path superimposed upon said master film, and means for producing light for transmission 30 through said master film to said sensitized film.

In testimony whereof I have hereunto affixed my signature in the presence of the two subscribing witnesses.

ISIDOR KITSEE.
